UNITED STATES PATENT OFFICE.

CHARLES N. TYLER, OF BUFFALO, NEW YORK.

FLUID-DISCHARGE DEVICE.

SPECIFICATION forming part of Letters Patent No. 378,812, dated February 28, 1888.

Application filed April 5, 1887. Serial No. 233,771. (No model.)

To all whom it may concern:

Be it known that I, CHARLES N. TYLER, a citizen of the United States, residing at Buffalo, Erie county, New York, have invented 5 certain new and useful Improvements in Fluid-Discharge Devices, of which the following is a specification.

My invention relates to a contrivance for withdrawing the liquids from receptacles; and 10 it consists of a discharge-tube pivotally connected to the lower portion of the receptacle, constructed and adjustable as fully set forth hereinafter, and as illustrated in the accompanying drawings, in which—

15 Figure 1 is a side view of a receptacle provided with two forms of my improved discharge contrivance. Fig. 2 is a view illustrating a different connection of the contrivance with the vessel. Fig. 3 is an enlarged 20 sectional view of said contrivance. Fig. 4 is a detached sectional view of the discharge-tube.

For the purpose of illustrating my invention I have shown it in Fig. 1 in connection 25 with an oil-can, A; but it will be understood that it may be combined with various different receptacles, which I shall designate under the term "receptacle." The said receptacle A has near the bottom a socket or opening, 30 within which fits a metal casing, B, having a packed socket for the reception of the horizontal portion of an L-shaped tube, C, which can turn in said casing to either a horizontal, vertical, or any intermediate position, and 35 which is preferably provided at the upper end with a curved terminal or siphon section, 3, fitting a packed box, 4, carried by the tube C, so that the section 3 may be revolved to carry its curved end to any desired side. With the 40 interior of the casing B communicates a short pipe, 5, to which is applied the lower end of a flexible tube, E, provided with a glass section, 6, having graduations thereon, which glass section is in the line of said tube. The 45 receptacle A is provided with a finger or projection, 8, upon which the tube E may be hung in such position that the level of the fluid in the receptacle will be exhibited in the transparent section 6, and it will be evident that 50 by adjustment of the tube E the section 6 may be kept in position approximating the level of

the fluid, and the graduations upon the section 6 will indicate the changes in level which take place when the fluid is passing out of the receptacle.

55

So long as the level of the liquid is below that of the turn-up tube C the contents of the can will be retained therein; but if it be desired to withdraw any particular portion of the contents—say, for instance, the quantity 60 resulting from a change of level of one, two, or more inches, which quantity may be estimated from the size of the can—the tube C may be turned down to an inclined position, with its end sufficiently below the level of the 65 liquid in the receptacle to insure the flow of the desired quantity, and a suitable vessel may be placed beneath the spout of the tube C, and the liquid may run therefrom without further attention upon the part of the operator, the 70 flow of liquid ceasing as the level in the receptacle is in line with the discharge end of the tube.

By turning the nozzle 3 outward or to one side the fluid may be directed in such manner 75 as to facilitate its withdrawal, and the nozzle-section 3 may be smaller in diameter than the section C and slide therein, thus affording a means of changing the length of the delivery-section as may be desired, to facilitate the 80 operation. Such a construction is illustrated in Fig. 4, which is a sectional view enlarged, and shows an ordinary telescopic fluid-tight joint uniting two circular tubes, the lower one or discharge-tube, C, being the larger, while 85 the nozzle-section 3 is of smaller size and fits therein. The upper end of tube C is enlarged and externally screw-threaded to receive the nut or cap K, through which passes the section 3, and which serves to confine the 90 packing material L against the end of tube C closely around the smaller tube of section 3. The lower end of tube-section 3 is provided with a head or flange, 3', by which accidental removal is prevented.

95

Instead of applying the casing B to the socket in the vessel, I in some instances connect said casing to a pipe, G, connecting with the bottom of the vessel, as shown in Fig. 3, this construction being serviceable when the vessel must 100 be placed in an elevated position.

The metal casing B is simply a packing-box,

in which is mounted the horizontal arm of the discharge-tube, and may be of any desired or preferred construction so long as it permits the arm or pipe C to turn fluid-tight therein; but 5 in order that its construction may be better understood to those skilled in the art, I have in Fig. 3 illustrated by an enlarged sectional view the construction shown to the right-hand side of Fig. 1, and will now proceed to describe 10 its parts in detail.

The socket or casing B is hollow, and receives the end of pipe G, which may be secured thereto by screw-threads (not shown) or by the 15 annular head or flange g, which prevents the withdrawal of the socket B from the tube when not united by screw-threads. The end of the horizontal portion of the discharge-tube C is also provided with a head or flange, c, adapted to enter the opening (which is enlarged there- 20 for) in socket B, and to lie close to flange g on pipe G.

I is a sleeve surrounding the horizontal portion of the discharge-tube, and provided externally with a screw-thread, i, by which it is 25 united with the socket B, it being adapted to bescrewed up close to flange c, and thereby confine the discharge-tube in casing or socket B.

H is a nut surrounding tube C and engaging with threads i of sleeve I, and forming there- 30 with a box adapted to receive the packing h.

From the above description and an examination of the drawings, it will be seen that the discharge pipe or tube may be turned in the casing B to a more or less inclined position 35 without the danger of disconnecting the parts or causing the same to leak.

When pipe G is dispensed with, identically the construction just described may be used, (with the exception of part G,) the casing or socket B being inserted directly into the receptacle A. However, I do not wish to be limited 40 to the precise construction described.

Without limiting myself to the precise construction and arrangement of parts shown, I 45 claim—

1. The combination of a receptacle, A, a discharge-tube, and a separate pipe containing a transparent graduated section, said section being vertically adjustable relatively to the fluid-line, substantially as set forth.

2. The combination of the receptacle A, discharge-tube C, pivotally connected therewith, flexible pipe E, and transparent section 6 in the line of said pipe, substantially as set forth.

3. The combination of a receptacle, A, a socket-piece, B, inserted therein, an L-shaped tube, C, turning in said socket, a nozzle section, 3, of smaller size than said L-shaped section, sliding therein and also turning around its longitudinal axis, and a fluid-tight connection between tube C and the nozzle-section, 55 substantially as set forth.

In testimony whereof I have signed my name to this specification in the presence of two subscribing witnesses.

CHARLES N. TYLER.
